UNITED STATES PATENT OFFICE

EDWARD JACOBS, OF NEW YORK, N. Y.

DESIGN FOR A CAPSULE FOR CARBONATING LIQUIDS

Application filed April 19, 1932. Serial No. 43,540. Term of patent 14 years.

To all whom it may concern:

Be it known that I, EDWARD JACOBS, a citizen of the United States, residing in New York, county and State of New York, have invented a new, original, and ornamental Design for a Capsule for Carbonating Liquids, of which the following is a specification, reference being had to the accompanying drawing forming a part thereof.

The figure is a side elevation of a capsule for carbonating liquids showing my new design.

I claim:

The ornamental design for a capsule for carbonating liquids as shown.

EDWARD JACOBS.
